LEATHER TOPPED RUBBER FOOTWEAR

Conrad Ferrettie, Mishawaka, Ind., assignor to
Mishawaka Rubber and Woolen Manufacturing Company, Mishawaka, Ind., a corporation of Indiana

Application May 19, 1941, Serial No. 394,043

6 Claims. (Cl. 36—4)

My invention relates to footwear of the type wherein a rubber foot portion is provided with a leather top or upper which is secured along its lower margin to the top margin of the rubber foot portion, and has reference more particularly to the method of and means for securing these two parts together.

Heretofore, in making this type of footwear, it has been customary to attach the leather top or upper to the rubber foot portion after the latter is vulcanized, a substantial width along the lower margin of the leather top being applied externally over a corresponding width along the upper margin of the rubber foot portion and secured thereto by a number of rows of stitching passing through the overlapped margins.

These previous structures, however, have a number of disadvantages. The joining section is undesirably heavy with an uncomfortable ridge inside the shoe due to the upper edge of the rubber margin that is exposed therein and as this edge is presented upwardly it interferes annoyingly in sliding the foot into the shoe and in the rubbing action thereagainst that occurs in inserting the foot is likely to be pulled away sufficiently from the shoe wall to cause even greater annoyance and discomfort. Also in these prior structures the stitching was exposed and unprotected at the outer side of the shoe and these stitches, as well as the lower edge of the leather upper were exposed to scuffing. Various expedients have been resorted to in order to protect the exposed stitches and the lower edge of the leather, such as covering these portions with an added layer of rubber but these expedients usually increased the bulkiness of the joint and did not lend themselves to simplicity and economy of construction or neatness of appearance.

The principal objects of my invention are to simplify the construction and improve the serviceability and appearance of footwear of the type above referred to; to insure a strong and dependable connection of the leather upper to the rubber foot portion without bulkiness; to provide a smooth comfortable surface at the joint inside the shoe and neat finished appearance at the outside; to thoroughly protect the stitches against external exposure and scuffing; to incorporate these improvements in the structure without extra or special parts or added expense; and to facilitate the manufacture of the shoe as a whole—these and other objects being

accomplished as pointed out hereinafter and as shown in the accompanying drawing, in which

Fig. 1 is a perspective view of an article of footwear constructed in accordance with my invention, portions thereof being broken away to disclose details of the construction;

Fig. 2 is a perspective view of the lower portion of the leather top as it is assembled with attached foot lining for making a shoe in accordance with this invention;

Fig. 3 is an enlarged fragmentary sectional view on the line 3—3 of Fig. 2; and

Fig. 4 is a similar section taken on the line 4—4 of Fig. 1.

Referring to the drawing, the reference numeral 10 indicates the rubber foot portion of the shoe and 11 the leather top or upper to which the foot portion 10 is attached. The leather upper 11 may be of conventional form either composed of separate quarters 12 joined together at the back under a back stay 13 as indicated in Fig. 2 or the two quarters may be portions of a single piece of leather that is continuous across the back of the shoe. A bellows tongue 14 is secured to the forward edges of the quarters 12, both of which have matching eyelets 15 at intervals down the front for lacing the quarters together over the bellows tongue, and the lower portion of this bellows tongue, which is interposed between and connects the separated lower ends of the quarters 12 at the front so that there is a continuous margin around the bottom of the leather upper, is secured, like the lower portions of the quarters 12, to the top of the rubber foot portion 10.

The rubber foot portion 10 is also for the most part of conventional construction consisting generally of insole 16, rubber outsole 17 (with or without rubber heel 18 as preferred) and rubber foot enclosure or wall 19 of approximately ankle height extending upwardly from the rubber sole 17 and provided with a fabric lining 20, the lower edge of which is lasted between the outsole 17 and margin of the insole 16 in the usual manner, it being understood that the rubber foot portion 10 is appropriately stiffened and reinforced as required in accordance with usual practice although such stiffening and reinforcing is not fully shown nor described in detail since it forms no part of the present invention.

Instead, however, of securing the lower margin of the leather upper 11 to the outside of the upper margin of the rubber foot portion 10 which is the common and prevailing practice in making footwear of this character and has the disad-

vantages above mentioned, I interpose the lower margin 21 of the leather upper 11 between the upper margin of the rubber wall 19 and the upper margin of the lining 20 and secure this leather margin 21 by several rows of stitches 22 directly to the lining 20 and also directly to a reinforcing fabric strip 23 which is attached securely in any convenient manner to the lining 20 below the leather margin 21 as indicated at 24.

The rubber wall 19 overlies the fabric strip 23 and is vulcanized thereto and thus covers the outer ends of the stitches 22 and seals the stitch openings so that the stitching is thoroughly protected against exterior exposure and scuffing, and moreover this construction affords a neat and finished appearance at the joint which may be enhanced by forming the rubber wall 19 along its upper margin with rib or bead formations 25 if desired.

Moreover the lower edge of the leather upper is enclosed between the fabrics 20 and 23 and tightly stitched between the fabrics 20 and 23 which are also preferably adhesively bonded to the leather, and thus the leather upper is not only firmly secured to the rubber foot portion 10 but a smooth surfaced joint is provided at the inside of the shoe which avoids the discomfort and annoyance experienced with previous leather topped rubber footwear of this character.

In manufacturing footwear in accordance with this invention the foot lining 20 and fabric reinforcing 23 are attached to the lower margin 21 of the leather upper as shown in Figs. 2 and 3 before the foot portion 10 is assembled and vulcanized.

In preparing this combined leather upper and foot lining, the lining blank, which is frictioned or gum coated over the entire outer surface is shaped in approximately the foot covering form as shown in Fig. 2 with the ends taped together at the back as shown at 26 and notched and taped at the toe as indicated at 27 and this lining blank is cemented along its upper margin to the inside of the lower margin 21 of the leather upper. The reinforcing strip 23 which extends entirely around the shoe is frictioned or gum coated on both sides and cemented to the outer side of the leather margin and a substantial width of this strip 23 extends below the leather margin 21 and is firmly cemented to the lining 20. A number of rows of stitches 22 are applied entirely through the fabrics 20 and 23 and the intermediate leather margin 21 either before or after the cementing of the lower portion of the strip 23 to the lining 20.

The thus assembled leather upper and foot lining is then applied on a last, and the rubber foot portion 11 built up thereon in the usual manner of assembling rubber footwear with the lower margin of the lining 20 lasted between the insole 16 and outsole 17 and the rubber side wall 19 adhesively secured to the lining 20 and extended upwardly over the fabric strip to which it is also adhesively secured, and after being thus assembled the entire structure is placed in a vulcanizer and the rubber portions thereof vulcanized, care being taken that the vulcanizing temperature is not sufficient to dry up any moisture in the leather and cause the latter to burn.

A vulcanizable rubber cement is employed in adhesively securing the various parts together and when thus vulcanized all of the cemented parts are securely bonded together and the leather upper inseparably secured to the rubber foot portion.

Instead of having the lining 20 at the inner side

5 of the leather margin 21 and the fabric strip 23 at the outer side thereof, these parts may be reversed with the lining 20 continued up between the rubber wall 19 and the leather margin 21 in which case the fabric strip 23 would be located at the inside of the shoe and cemented to the inner face of the lining 20 and be secured to the inner surface of the leather margin 21. The lining 20, or the fabric 23 if these parts are reversed, may 10 of course be continued up to the top of the leather upper 11 if desired.

While I have shown and described my invention in a preferred form I am aware that various modifications can be made without departing from 15 the spirit of my invention, the scope of which is to be determined by the appended claims.

I claim as my invention:

1. An article of the class described having a waterproof foot portion and an upper of non-waterproof material, said foot portion having a lining comprising inner and outer layers between which the lower margin of the upper is secured by mechanical fastenings, and said foot portion having a layer of waterproof material thereon secured to the outer face of the aforesaid outer lining layer and covering said mechanical fastenings.

2. An article of footwear of the class described having a leather upper and a fabric lined vulcanized rubber foot portion, the fabric lining having inner and outer laminations which extend around the top of the foot portion and have the lower margin of the leather upper secured therebetween, and the vulcanized rubber of the foot portion being extended over and vulcanized to the outer face of the outer fabric lamination.

3. An article of footwear of the class described having a leather upper and a fabric lined vulcanized rubber foot portion, a reinforcing strip of fabric extending around the foot portion at the top and spaced from the corresponding portion of the lining to accommodate the lower margin of the leather upper therebetween, rows of stitches extending around the top of the rubber foot portion and engaged through the lining and reinforcing strip and the interposed margin of the leather upper to secure the latter to the rubber foot portion, and said foot portion having a side wall of rubber therearound extending over and vulcanized to the outer surface of the outermost fabric and covering the outer ends of the stitches.

4. An article of footwear of the class described having a leather upper and a vulcanized rubber foot portion, said foot portion having a fabric lining with inner and outer laminations between which the lower margin of the leather upper is adhesively secured, a plurality of rows of stitches around the top of the rubber foot portion extending through both fabric laminations and the interposed leather margin, and said rubber foot portion having an outer surrounding wall of vulcanized rubber extended over and vulcanized to the outer face of the outer lamination so as to cover the outer ends of the stitches and seal the stitch openings.

5. An article of footwear of the class described comprising, a leather upper, a rubber foot portion of substantially ankle height, a fabric lining within said foot portion and extending approximately to the top thereof, said leather upper extending below the upper edge of said lining in overlapping relation therewith, a reinforcing strip of fabric on the side of the overlapping portion of said upper opposite the lining,

rows of stitches engaged through said lining, reinforcing strip and interposed overlapping portion of the upper to secure the upper to the foot portion, the rubber of said foot portion extending over the area of said rows of stitches and covering the outer ends thereof.

6. An article of footwear comprising a leather upper and a rubber foot portion, said foot portion having a fabric lining therein and extending upward to substantially ankle height, the lower margin of said upper overlapping the upper

edge of said lining on the outer side thereof, a reinforcing strip of fabric extending around the lower margin of said upper on the side thereof opposite the lining, rows of stitches engaged through said lining and reinforcing strip and the interposed margin of said upper to secure the latter to the foot portion, the rubber of said foot portion extending over the reinforcing strip and covering the outer ends of said stitches.
